[57] CLAIM

The ornamental design for an electronic scanner for retrieving stored data from the sidewall of a tire, as shown and described.

DESCRIPTION

FIG. 1 is a perspective view of an electronic scanner for retrieving stored data from the sidewall of a tire;
FIG. 2 is a left side elevational view thereof;
FIG. 3 is a front elevational view thereof;
FIG. 4 is a right side elevational view thereof;
FIG. 5 is an end elevational view thereof;
FIG. 6 is a top elevational view thereof;
FIG. 7 is a bottom elevational view thereof;
FIG. 8 is a top view similar to FIG. 6 wherein one end of the electronic reader device is illustrated in an alternative orientation relative to the other portion of the reader as shown in the preceding figures; and,
FIG. 9 is a left side view of the electronic scanner for retrieving stored data from the sidewall of a tire oriented as shown in FIG. 8.
